UNITED STATES PATENT OFFICE

WAYNE H. WORTHINGTON, OF INDEPENDENCE, MISSOURI, ASSIGNOR TO THE GLEANER COMBINE HARVESTER CORPORATION, OF INDEPENDENCE, MISSOURI, A CORPORATION OF DELAWARE

WINDROWING MACHINE

Application filed November 15, 1929. Serial No. 407,390.

My invention relates to windrowing machines, and more particularly to machines of that character for cutting and windrowing wheat or similar crops that require time to mature before they are in condition for threshing.

The principal objects of the invention are to provide a rugged machine wherein the cutting mechanism is suspendingly balanced from the main frame, and to provide a supporting framework which is extremely rigid, and wherein certain torsional strains are equalized by opposed strains inherently constructed in the frame.

15 In accomplishing these and other objects of the invention, I have provided improved details of structure, the preferred form of which is shown in the accompanying drawings, wherein:

20 Fig. 1 is a perspective view of the front of a machine constructed in accordance with my invention.

Fig. 2 is a perspective view of the rear of the machine.

25 Fig. 3 is a plan view of the machine.

Fig. 4 is a rear elevational view of the machine, particularly illustrating the trusses and brace members of the frame.

30 Fig. 5 is a longitudinal sectional view through the machine on the line 5-5, Fig. 4.

Fig. 6 is a detail perspective view of a portion of the machine, illustrating the mechanisms for operating and adjusting the cutting unit.

35 Fig. 7 is an elevational view of the trusses for trussing the cutting unit, parts of which are broken away to better illustrate the construction.

40 Fig. 8 is an enlarged cross sectional view through a longitudinal portion of the main frame, particularly illustrating the brace member for inherently tensioning the frame.

Fig. 9 is a detail sectional view through the grain wheel, particularly illustrating its 45 mounting and the pivotal connection of one of the arms supporting the cutting unit.

Fig. 10 is a sectional view on the line 10-10, Fig. 9, illustrating the pivotal connection of the supporting arms with the main frame.

Fig. 11 is a sectional view through an axle supporting bracket on the line 11-11, Fig. 9.

Referring more in detail to the drawings: 1 designates a main frame including spaced parallel channel members 2 and 3 and cross members 4 and 5, secured to the longitudinal members by gusset plates 6, 7, 8 and 9. In front of the cross member 5 the channel 2 is canted toward the longitudinal member 3, and their ends are connected at the top by a gusset plate 10, and at the bottom by a depending bracket 11, later described.

Extending laterally from and in the plane of the longitudinal members 2 and 3 is an I-beam 12 which is secured to the flanges of the channel 3 by gusset plates 13. The free end of the I-beam is braced by a channel member 14 which may be an extension of the cross member 4, and is secured to the outer end of the I-beam 12 by upper and lower gusset plates 15 and 16.

The channel member 14 thus described braces the I-beam 12 in one direction, and to brace the beam in the opposite direction and to stiffen the frame, I provide an I-beam 17 positioned diagonally across the channel members 2 and 3 and across the I-beam 12 to the brace member 14, as clearly illustrated in Fig. 3.

Fig. 11 is a detail sectional view through an axle supporting bracket on the line 11-11, Fig. 9. The beam is bolted to the longitudinal members 2 and 3, the beam 12 and brace 14, the outer end of the beam being supported on the gusset plate 8 above the plane of the longitudinal member 3 and I-beam 12. Thus the I-beam, due to its rigidity, produces tension in the main frame whereby a lifting effect is produced on the channel member 3, and a loading effect is produced adjacent the outer end of the lateral beam 12 to equalize tensional forces exerted by the cutting unit, later described.

The framework thus described constitutes the main frame of the machine and is supported by a main traction wheel 21, a front steering truck 22, and a grain wheel 23 aligning with the traction wheel 21. The main wheel 21 is received in the rectangular space formed by the channel members 2, 3, 4 and 5, and is rotatably mounted on an axle 24 that is supported in the brackets 26 and 27 bolted

to the lower flanges of the longitudinal members, as shown in Fig. 4, in alignment with the lateral beam 12.

The grain wheel 23 is rotatably mounted on a stub axle 28 having one end clamped in a bearing bracket 29 which is bolted to the lower flanges of the lateral beam 12, the bracket being provided with laterally extending flanges 30, having openings 31 for receiving bolts 32 that are projected through openings of flanges of the angle, as best illustrated in Fig. 11. Formed integrally with the lower portion of the bracket are slotted sleeves 33 and 34 for receiving the axle 18 which is clamped therein by bolts 35 extending through aligning ears 36 formed on the sleeve portion of the bracket. The grain wheel 23 is retained on the axle by a brace supporting member 37, later described.

The depending bracket 11 previously described is for mounting the steering truck 22 and is provided with a cylindrical bore aligning with a similar bore in a bracket 38 depending from the lower flanges of the longitudinal members 2 and 3, as shown in Fig. 5.

Extending through the bores of the brackets and rotatably mounted therein is a trunnion member 39, and secured to the front end of the trunnion is the axle 40 carrying the wheels 41 of the front truck. The trunnion 39 is retained against longitudinal movement in the brackets by collars 42 and 43 clamped to the trunnion at opposite sides of the bracket 11, as best shown in Fig. 5. The front truck may be provided with any suitable draft rigging such as a tongue 44.

Supported within the angle formed by the longitudinal member 3 and the lateral beam 12 is a secondary frame for carrying the cutting unit of the machine, and which comprises a rectangular frame 45 including spaced, parallel angles 46 and 47 extending parallel with the lateral beam 12, and connecting the angles 46 and 47 are a plurality of spaced angle bars 48, 49, 50, 51 and 52, each having their horizontal flanges bolted to the lower side of the horizontal flanges on the angles 46 and 47, as illustrated in Figs. 4 and 5.

Supported from and attached to the angle 46 of the horizontal framework, just described, are spaced, vertical angles 53 connected at their upper ends by an angle bar 54 extending parallel with the angle bars 46 and 47, previously described.

Riveted to the vertical flanges of the angle bars 46 and 54, and extending from the outer end of the secondary frame to a point between the traction wheel and the grain wheel, is a sheet metal plate 55, and formed in the plate about midway of the grain and traction wheels is an opening 56, through which the cut grain is discharged into a windrow as the machine progresses over the field, as later described.

In order that the machine may be passed through a gate or the like, the cutting unit preferably includes a detachable section at its outer end which is secured to the main section at a point substantially in alignment with the outer side of the grain wheel as indicated by the abutting angles 53 (Fig. 4).

Operably supported on the horizontal portion of the secondary frame on rollers 57 and 58 is a canvas type conveyor 59, and supported on the front angle bar 47 is a sickle 60 for cutting the grain which is to be deposited by the conveyor into windrows, as later described.

Bolted to the vertical portion of the secondary frame at opposite ends of the sickle bar are forwardly projecting arms 61 and 62 for supporting a reel 63 of ordinary construction. The arm 61 projects rearwardly of the secondary frame and is adjustably braced by a bar 64 bolted to the lower end of the outer angle member 53 and to the projecting end of the arm 61, and the arm 62 is adjustably supported adjacent its outer end by a vertical post 65 that is pivotally supported by the front angle member 47. The cutting unit thus described is pivotally supported from the main frame as now described.

Bolted to the cross bars 48, 49, 50 and 51 are rearwardly and upwardly inclined arms 66, 67, 68 and 69, respectively. The arms 66 and 69 are pivoted on the axles 24 and 28 by castings 70 bolted to the rear ends of the arms by bolts 71 projecting through plates 72 on the castings and through the arms, as best illustrated in Figs. 9 and 10.

Formed integrally with the plates 72 are cylindrical bearing sleeves 73 adapted to receive the axles 24 and 28 between the spaced sleeves 29 and 30 of the bracket member supporting the grain wheel and between similar sleeves 74 and 75 on the bracket member 27 supporting the axle shaft 24.

The arms 67 and 68 are pivoted to brackets 76 and 77 bolted to the lower flange of the lateral beam 12, as shown in Fig. 4, the brackets being provided with spaced depending ears 78 for receiving therebetween the ends of the arms 67 and 68, which are pivotally attached thereto by bolts 79 projecting through the ears 78 and through the ends of the arms. The ears 78 are of sufficient length to position the pivotal point of the arms in alignment with the axes of the wheel shafts, so that the secondary frame can pivot on the axes of the wheels 21 and 23.

80 and 81 designate brace members for connecting the rear ends of the arms with the upper ends of the adjacent angles 53 on the secondary frame, as shown in Figs. 2 and 5, whereby the vertical portion of the secondary frame is braced in vertical alignment with the horizontal portion of the frame.

In order to rigidly support the secondary frame and prevent sagging which would in-

terfere with the operation of the sickle bar, I provide truss members 82 and 83, now described. The truss member 82 includes a channel-shaped compression member 84 and a bar-shaped tension member 85 having its ends bolted to the ends of the member 84 by bolts 86 and 87, as illustrated in Fig. 7. The members 84 and 85 are formed to provide a substantially diamond-shaped truss member, and are spaced apart by a vertical compression member 88, later described.

The respective ends of the truss member 82 are bolted to an angle extension 89 projecting from the angle 54 of the secondary frame by a bolt 90 projecting through an opening 91 in the end of the truss, and through a similar opening in the angle 89. The opposite end of the truss is connected by an ear 92 which is retained between the ends of the members 84 and 85, and the ear is bolted to the rear end of the arm 69 adjacent the casting member 70 by a bolt 93 extending through an opening 94 in the ear and through a similar opening in the arm.

25 The truss thus described is inter-connected with the truss 83 which comprises a channel-shaped compression member 95 extending from a point adjacent the rear end of the arm 66 to connect with the secondary frame adjacent the upper end of the brace member 81, and the ends of the member are secured by ears 96 and 97 similar to the ear 92.

35 The compression member 88 comprises a tubular sleeve 98 supported vertically between the tension member 85 and the compression member 84 of the truss 82, and extending through an opening 99 in the member 84, through openings 100 and 101 of the tension members 102 and 103, through the sleeve 98, and through aligning openings 104 and 105 in the members 85 and 95, respectively, is a bolt 106. The bolt 106 is threaded on its lower end to receive a nut 107 to clamp the truss members together and retain them in 45 co-related position.

40 The tension members 102 and 103 preferably comprise rods having their free ends flattened for attachment to the ends of the compression member 95 by bolts 108 and 109. The tension members 102 and 103 are also provided with turn buckles 110 and 111, whereby tension of the trusses may be adjusted to position the secondary frame in proper alignment.

55 The outer end of the secondary frame is provided with a diagonally extending brace member 112 complementary to the arms 66 to 69, and which is bolted to the retaining member 37 received on the end of the axle shaft 28 previously mentioned.

The member 37 comprises a sleeve having ears 113 and 114 for attaching the arm 112 by bolts 115 which project through the ears and through the angle, as best shown in Fig. 2. Projecting upwardly from the retaining

member 37 is a lug 116 having an opening 117 for receiving a rod 118. The rod 118 is bolted to the outer vertical member 53 of the secondary frame, as at 119, and the opposite end is adjustably retained in the lug 116 by nuts 120 and 121 threaded onto the rod and engaging opposite sides of the lug. Thus the outer end of the secondary frame is braced rearwardly from the axle supporting the grain wheel, and upon movement of the secondary frame the retaining member 37 is adapted to rock on the axle similarly to the member 70, pivoting the connecting arms 66 and 69.

70 The retaining member 37 is secured on the axle by a washer 122 received on a stud 123 projecting from the end of the axle, and which is threaded to receive a retaining nut 124, as shown in Fig. 9.

75 In order to adjustably support the cutter bar with relation to the height of grain being cut, I provide a raising and lowering mechanism now described.

80 Rotatably supported in bearings 125 and 126, mounted respectively on the longitudinal frame members 2 and 3, is a rock shaft 127, and on the inner end of the rock shaft is a cam-shaped segment 128 adjacent to the forwardly projecting arm 129 preferably integrally formed on the end of the rock shaft 127, and to which is secured the cam segment by U-bolts 130 extending over the arm and through the segment, as shown in Fig. 6.

85 Fixed adjacent the forward end of the arm 66 is an ear 131 having an opening 132 to receive a laterally projecting end 133 of a connecting link 134, having its upper end bent laterally to be received in an opening 135 in the end of the arm 129, whereby the arm 129 is connected to the secondary frame.

90 In order to rock the shaft 127 for lifting the secondary frame, I provide the shaft with a worm gearing designated by the housing 136 which is operated by a shaft 137 extending forwardly of the machine and rotatably mounted in spaced brackets 138 and 139 projecting upwardly from the main frame.

95 The end of the shaft 137 is provided with a hand wheel 140, whereby the shaft may be rotated to actuate the rock shaft 127 for lifting the secondary frame.

100 In order to balance the unit of the secondary frame and to assist in easy operation of the shaft 137, I provide springs 141 and 142 having one of their ends attached to an upward extension 143 of the gusset plate 7, and the other ends connected with a plate 144.

105 Fixed to the plate 144 by U-shaped clamps 145 is a cable 146 having its free end extended in a groove 147 formed in the periphery of the cam segment and clamped thereto by a clamping plate 148 secured by one of the U-bolts 130.

110 The cam groove 147 is so shaped that the cam compensates for the varying tension of 130

the springs as the cutting unit is raised or lowered with relation to the main frame so that the cutting unit is balanced by the springs regardless of its position or the ⁵ tension of the springs.

Fixed to the side of the main traction wheel and rotatable therewith on the axle shaft 24 is a sprocket 149, and aligned with the sprocket 149 is a sprocket 150 loose on the ¹⁰ countershaft 151, which is rotatably mounted on the secondary frame adjacent the end of the angle member 46. The countershaft 151 is supported by bearings 152 and 153 secured to the angles 48 and 49, respectively. ¹⁵ The sprocket wheel 150 is driven from the sprocket 149 by a chain 154 operating over the sprockets.

In order to rotate the countershaft from the gear 150, I provide a clutch member 155 having teeth 156 adapted to engage similar teeth 157 on the hub of the sprocket 150, the clutch being operated by a bell crank lever 158, having one end engaging the clutch member 155 and the other connected with a flexible cable ²⁰ 159 running over a pulley on the frame, having its free end attached to an actuating lever 160; the lever 160 preferably being supported adjacent the front end of the channel member 3 by a bracket 161. ²⁵ Fixed on the countershaft 151 is a sprocket wheel 162, and operating thereover and over a sprocket wheel 163 on the reel shaft is a chain 164 so that when the countershaft clutch is engaged with the sprocket 150, the ³⁰ countershaft operates the reel to bring the grain into contact with the sickle bar. Also fixed on the countershaft between the sprocket wheel 150 and the sprocket wheel 162 is a sprocket wheel 165 aligned with a ³⁵ sprocket wheel 166 for operating a transmission mechanism indicated by the housing 167; the sprocket 166 being driven by a chain 168 operating over the sprockets.

The transmission housing 167 is supported ⁴⁰ on the horizontal portion of the secondary frame adjacent the inner end of the angle member 47. Extending longitudinally through the housing is a power delivery shaft 169 having a crank 170 on its forward end for actuating the sickle bar through a pitman 171. The opposite end of the shaft 169 is provided with a clutch 172 for operably connecting an aligning shaft 173 rotatably supported on the secondary frame. Fixed to the outer ⁴⁵ end of the shaft is a sprocket 174 for actuating the canvas conveyor as now described.

Fixed on the roller shaft 58 of the conveyor is a sprocket 175 and operating over the sprocket, idling sprockets 176 and 177, and ⁵⁰ over a sprocket 178 is a chain 179. The sprocket 178 is rotatably mounted on a stub shaft 180 projecting rearwardly of the vertical portion of the secondary frame (Fig. ⁵⁵ 4), and operable on the stub shaft with the sprocket 178 is a sprocket 181 driven by a

chain 182 running over the sprocket 174, idlers 183 and 184, and the sprocket 181, whereby the conveyor is driven from the sprocket 174 through the chains 182 and 179.

Pivotedly supported by the secondary ⁷⁰ frame crosswise of the end of the conveyor is a stubble breaker 185 for bending over the grain stubble to support the deposited windrow, as hereinafter described. The stubble breaker 185 comprises a plate 186 having upwardly extending side flanges 187 and 188, and fixed to the lower face of the guard are ribs 189. The guard 185 is pivoted to the secondary main frame by bolts 190 extending through the front ends of the flanges ⁷⁵ 187 and 188, and through adjacent supporting members on the secondary frame. The guard is functionally supported in an adjustably inclined position by a bar 191 having its lower end pivoted to the flange 187 and its ⁸⁰ upper end supported by a crank 192.

The crank 192 is rotatably mounted in a bearing 193 formed on a bracket 194 projecting from the vertical portion of the secondary frame; and rotatably mounted in a sleeve ⁹⁰ 196 on the bracket is a shaft 197, and fixed to the outer end of the shaft is an eccentrically mounted disk 198 having its periphery engaging and supporting the crank 192 so that the stubble breaker 185 may be raised or lowered upon rotation of the eccentric disk 198, as specifically described in a co-pending application filed even date herewith. ⁹⁵

The disk is rotated by a pulley 199 loosely mounted on the shaft but adapted to be connected with the disk by a clutch face 200 on the pulley engageable with a similar clutch face on the disk when the pulley is rotated by the cable 201 in a clockwise direction (Fig. 6). ¹⁰⁰

Fixed to the center of the disk 198 is a rod 202 connected with a laterally extending arm 203 of a rock shaft 204 rotatably mounted longitudinally of the angle 48. Fixed on the end of the rod is an arm 205 having a finger ¹⁰⁵ 206 adapted to engage the clutch 172 for stopping rotation of the shaft 173 when the stubble breaker is in raised position.

In operating a machine constructed and assembled as described, the machine is drawn over the field and rotation of the main wheel 21 operates the countershaft 151 to actuate the sprockets 165 and 166 for operating the shaft 169 to drive the sickle bar. ¹¹⁰

The reel is also actuated from the countershaft through the sprockets 162, 163 and chain 164, to bring the grain into engagement with the sickle bar. The cut grain then falls on the conveyor and is discharged at the end thereof onto the stubble breaker 185, from which it slides off to be deposited in a windrow supported by the stubbles of the grain laid over thereby. ¹¹⁵

During travel of the machine the secondary frame may be adjusted with relation to ¹²⁰ 130

the height of the grain by operating the shaft 137 to rotate the rock shaft 127 for actuating the cam crank arm 129, as previously described.

5 When it is desired to stop operation of the platform-conveyor, the pulley 199 is actuated by the cable 201 to cause the disk 198 to rotate and lift the stubble breaker 185, which at the same time causes the finger 26 on the arm 205 to engage the clutch 172 and stop operation of the conveyor.

Actuation of the sickle bar and the reel may be controlled through the clutch 158 by operating the lever 160.

15 What I claim and desire to secure by Letters Patent is:

1. In a machine of the character described, a frame having a longitudinally extending portion and a laterally extending portion, 20 wheels supporting the frame, a secondary frame, arms fixed to the secondary frame and pivoted to the laterally extending portion of the main frame, crossed trusses connecting pivoted ends of each of the arms with the secondary frame for bracing the secondary frame, and braces connecting the pivotal ends of the arms with the secondary frame.

2. In a machine of the character described, 30 a main frame, a secondary frame, arms fixed to the secondary frame, and pivotally connected with the main frame, means for supporting the secondary frame with the main frame at one end thereof, tension and compression members connecting the secondary frame adjacent its supported end with one of the arms adjacent its pivotal connection with the main frame, a compression member supported between the members, a third member connecting the other arm with the secondary frame adjacent its outer end, and tension members connecting the ends of the last named member with the compression member to support the opposite end of the secondary frame.

45 3. In a machine of the character described, a main frame having a longitudinally extending portion and a laterally extending portion, wheels supporting the frame, a secondary frame pivoted to the main frame within the angle formed by the longitudinally extending portion, a rock shaft mounted on the longitudinal portion of the frame, a cam on the rock shaft, an arm associated with the cam, a link connecting the arm with the secondary frame, a flexible member operable over the cam, a spring connected with the flexible member and the main frame to balance the secondary frame, and gearing on the rock shaft for actuating the rock shaft to move the secondary frame on its pivotal connection with the main frame.

60 4. In a machine of the character described, a main frame, a secondary frame pivotally connected with the main frame, a rock shaft on the main frame, a cam-shaped member on

the rock shaft, an arm on the rock shaft, a link connecting the arm with the secondary frame, a flexible member operable over the cam member, means connected with the flexible member to balance the secondary frame 70 on its pivotal connection with the main frame, and gearing on the rock shaft for actuating the rock shaft to move the secondary frame with relation to the main frame.

5. In a machine of the character described 75 including a frame having a longitudinally extending portion and a lateral portion extending from the longitudinal portion, a grain wheel for supporting the free end of the lateral portion, an axially aligned traction 80 wheel for supporting the rear of the longitudinal portion of the frame, a front truck for supporting the front end of the longitudinal portion, a cutting unit including a rectangular frame having a vertical extension, 85 supporting arms attached to the rectangular frame and pivoted to the lateral extension of the main frame in axial alignment with the grain and traction wheels, cross trusses having their ends connected with the arms and 90 with the vertical extension of the rectangular frame for trussing the cutting unit, and means on the longitudinally extending portion of the main frame for raising and lowering the cutting unit on its pivot. 95

6. In a machine of the character described, 100 a main frame, axially aligned wheels supporting the frame, a secondary frame pivoted to the main frame in axial alignment with the wheels, a rock shaft on the main frame, a cam-shaped member on the rock shaft, means connecting the cam-shaped member with the secondary frame, means operable over the cam for balancing the secondary frame, and means on the rock shaft for actuating the rock shaft 105 to raise the secondary frame on its pivotal connection with the main frame.

7. In a machine of the character described, 110 a frame including inner and outer longitudinally extending members, cross members connecting the longitudinally extending members, a laterally extending member fixed to the inner longitudinal member, a beam extending diagonally across the longitudinal members and the free end of the lateral member, means for securing the beam to each of the respective members including means for spacing the beam above the level of the outer longitudinal member to produce inherent tension in the frame for the purpose set forth. 115

8. In a machine of the character described, 120 a main frame, arms pivoted to the main frame in spaced parallel relation with each other, a secondary frame carried by said arms including a vertical portion and a horizontal portion, a truss member connecting the vertical portion of the secondary frame with one of the arms adjacent its pivot, a second truss member connecting the vertical portion of the secondary frame with the other arm adjacent 125 130

its pivotal connection, and a compression member interconnecting said trusses.

9. In a machine of the character described, a main frame, arms pivoted to the main frame, a secondary frame carried by said arms and crossed trusses positioned above the plane of the said arms for trussing the secondary frame.

10. In a machine of the character described, a main frame, arms pivoted to the main frame, a secondary frame carried by said arms, upright members on the secondary frame in substantial alignment with said arms, means bracing the upper ends of the upright members with the pivoted ends of the arms, and crossed trusses connected with the upright members and the arms to truss the secondary frame.

11. In a machine of the character described, a main frame, arms pivoted to the main frame, a secondary frame carried by said arms, upright members on the secondary frame in substantial alignment with said arms, means bracing the upper ends of the upright members with the pivoted ends of the arms, crossed trusses connected with the upright members and the arms to truss the secondary frame, and means for tensioning the trusses.

12. In a machine of the character described, a frame including inner and outer longitudinally extending members, a lateral member fixed to the inner longitudinal member, a beam extending diagonally of said members and resting on the inner member and the inner lateral member, an insert positioned between the outer member and the beam to raise the inner member above the outer member to inherently tension said frame, and means for securing the beam to the longitudinal and lateral frame members.

In testimony whereof I affix my signature.
WAYNE H. WORTHINGTON.
